COMPACTLY FOLDABLE SPRINKLER MEANS

Mary Turausky, Chicago, Ill.

Application August 30, 1950, Serial No. 182,187

6 Claims. (Cl. 299—101)

1

My invention relates to sprinkler structures which are made of foldable material so that they may be folded compactly, and be carried about in a lady's purse, or in the pocket of a garment when not in use.

An important object of my invention is to provide a device of the aforementioned character which may be quickly and readily unfolded and filled with liquid contents to be dispensed through the spout section thereof.

Another object of my invention is to provide a sprinkler device of the aforementioned character having a body formed with longitudinally pleated sides so that the device may be compactly folded.

A further object of my invention is to provide auxiliary handle means to facilitate the use of the structure as a sprinkler.

A still further object of my invention is to provide a locking belt means or strap means for maintaining the device in a compactly folded position preventing accidental opening or unfolding thereof.

A still further object of my invention is to provide in a structure of the aforementioned character, a spout section which will be conveniently folded with the remainder of the unit so that the same will lend itself to compact folding formation.

Other objects, ancillary advantages, and features inherent in my invention will become apparent from an examination of the accompanying drawings, bearing further elucidation in the ensuing description, wherein like symbols are utilized to designate like parts, and in which:

Fig. 1 represents a front view of my invention.

Fig. 2 represents a side view of Fig. 1.

Fig. 3 is a cross-sectional view taken, substantially, on the lines 3—3 of Fig. 1.

Fig. 4 is a longitudinal cross-sectional view taken, substantially, on the lines 4—4 of Fig. 2.

Fig. 5 is a perspective view showing preliminary steps taken in compactly folding my invention.

Fig. 6 indicates a perspective view of the compactly folded invention, occupying a minimum of space so that same may be carried in the pocket of a garment or in a lady's purse.

Referring to the various views, my invention consists of a body of substantially cylindrical formation 7, divided by two longitudinal pleated sections at opposite sides designated 13, so that the same may be folded similarly to folding a paper bag. To the body 7 is attached a bottom portion 8, and an angularly positioned and ar-

2

cuately-shaped section 10 to form a mouth or entry for the sprinkler section designated 11. It will be noted that the sprinkler section is made up so as to have an angular portion 20 at its top, and a sprinkler face 21 with perforations 12 is also positioned in angular relationship to the longitudinal axis of the unit, providing a crotch portion 22 at the bottom so that the sprinkler portion 11 may be conveniently folded in place as indicated in Fig. 5.

The device is provided with a manipulating handle 14, which is held in one hand, while an auxiliary handle 24 is held or grasped for lifting the sprinkler in order to permit the liquid contents within the body 7 to be dispensed through the openings 12.

The body is open at the top at 9, except for the portion that is partially closed by the arcuate section 10 which forms a mouth leading into the confines 23 of the sprinkler portion 11, so that liquid therein may be dispensed when held by both hands, one hand grasping the handle 14, the other hand grasping the auxiliary handle 24, and lifting the bottom of the sprinkler so as to permit the liquid contents to be dispensed through the pouring holes or sprinkler holes 12.

When not in use, the unit may be folded compactly, by folding inwardly the pleats 13 as indicated in Fig. 5 and then folding the sprinkler portion 11 on the crotch 22 at the same time folding transversely along the fold demarcations designated 16 and 17. After the folding is completed and the body is folded into three sections as indicated in Fig. 5, the unit is held in compactly folded position by means of the folding or retaining strap 15 having a snap-fastener 18, and on its free end 19 a mating snap-fastener to engage the snap-fastener 18, so that the entire unit may be carried compactly in the pocket of a garment or a lady's purse when not in use.

Although I have herein described rather succinctly the nature and use of my invention so that persons skilled in the art will have no difficulty apprising themselves of the teachings there-

of and, inasmuch as the disclosure is susceptible of various alterations, modifications, and improvements, I hereby reserve the right to all modifications, alterations, and improvements falling within the scope and spirit of my invention, as well as any modifications that are embraced in the accompanying drawings, and any that may come within the purview of the foregoing description; my invention to be limited only by the appended claims.

Having thus disclosed and revealed my inven-

tion, what I claim as new and desire to secure by Letters Patent is:

1. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, and an auxiliary handle secured to the outer surface of the said body and at right angles to the said first-mentioned handle.

2. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, an auxiliary handle secured to the outer surface of the said body and at right angles to the said first-mentioned handle, and sprinkler perforations on the face of the said sprinkler section.

3. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, and an auxiliary handle secured to the outer surface of the said body and at right angles to the said first-mentioned handle, the said sprinkler device being folded longitudinally by collapsing the said pleat portions, folding the said sprinkler section on the said crotch portion and folding the said sprinkler device twice on transverse lines to form a compactly folded arrangement.

4. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, an auxiliary handle secured to the outer surface of the said body and at right angles to the said first-mentioned handle, and sprinkler perforations on the face of the said sprinkler

section, the said sprinkler device being folded longitudinally by collapsing the said pleat portions, folding the said sprinkler section on the said crotch portion and folding the said sprinkler device twice on transverse lines to form a compactly folded arrangement.

5. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, an auxiliary handle secured to the outer surface of the said body and at right angles to the said first-mentioned handle, the said sprinkler device being folded longitudinally by collapsing the said pleat portions, folding the said sprinkler section on the said crotch portion and folding the said sprinkler device twice on transverse lines to form a compactly folded arrangement, retaining strap means having one end secured to the top of the said body and being of sufficient length to encircle the folded sprinkler device, and snap-fastener means for securing the two ends of the said retaining strap means.

6. A compactly foldable sprinkler device, comprising a body made of flexible material and having longitudinal pleat portions, an arcuately-shaped section partially closing the top of the said body defining a filler opening, a sprinkler section made of flexible material and formed contiguously to the said arcuately-shaped section and positioned to point obliquely upwardly forming a crotch portion at the point of juncture of the said sprinkler section with the said body, a carrying handle straddling the open top of the said body, an auxiliary handle secured to the outer surface of the said body and at right angles to the said first-mentioned handle, sprinkler perforations on the face of the said sprinkler section, the said sprinkler device being folded longitudinally by collapsing the said pleat portions, folding the said sprinkler section on the said crotch portion and folding the said sprinkler device twice on transverse lines to form a compactly folded arrangement, retaining strap means having one end secured to the top of the said body and being of sufficient length to encircle the folded sprinkler device, and snap-fastener means for securing the two ends of the said retaining strap means.
